UNITED STATES PATENT OFFICE.

EMANUEL E. NORQUIST, OF KANSAS CITY, MISSOURI.

STORAGE-BIN.

1,147,967.

Specification of Letters Patent.

Patented July 27, 1915.

Application filed May 17, 1915. Serial No. 28,777.

To all whom it may concern:

Be it known that I, EMANUEL E. NORQUIST, a citizen of the United States, residing at Kansas City, in the county of Jackson and 5 State of Missouri, have invented certain new and useful Improvements in Storage-Bins, of which the following is a specification.

This invention relates to storage bins for grain and the like and has for its object to 10 produce a bin partitioned into a plurality of chambers one of which is accessible through the customary door and the remainder of which are accessible from the door-controlled chamber.

15 Another object is to produce a partition embodying removable sections or slats between the door controlled chamber and each of the remaining chambers for making it possible to transfer the contents from either 20 of the last-named chambers to the door controlled chamber.

A further object is to produce a partition structure of such character that it can be positioned by the owner of the bin, to produce 25 chambers of relative capacity to hold the different grains or products or other articles to be stored.

With these objects in view the invention consists in certain novel and peculiar features of construction and organization as 30 hereinafter described and claimed; and in order that it may be fully understood reference is to be had to the accompanying drawing, in which—

35 Figure 1, is a top plan view with the cover omitted, of a grain bin shown provided with a partition embodying my invention. Fig. 2, is a section on the line II—II of Fig. 1.

In the said drawing, 1 is a bin of sheet 40 steel or equivalent material of a type in common use for the storage of grain, this bin being largely used upon the farms where the grain is raised as they are made rat and vermin proof, and are usually of knock-down 45 construction for convenience of portability. It is of frequent occurrence that a bin of this character is desirable for holding grain, bran, chops and the like for stock feeding purposes. To accomplish this purpose it is of course desirable that the bin be 50 provided with a partition dividing it into a plurality of chambers so that the same bin may hold about three different commodities and besides provide a chamber wherein such 55 commodities may be mixed, if desired, and sacked and a place for the storage of scoops,

sacks and other equipment which may be found convenient in the handling of the commodities. It is also necessary that the partition shall be of such character that it 60 shall successfully resist collapse under the imposition of pressure produced by the filling of but one or two of the chambers.

The partition is constructed as follows: 2 indicates several pairs of upright strips 65 which are secured rigidly to the inner side of the wall of the bin at the point selected by the person in control, the space 3, between each pair of the strips receiving the outer ends of boards 4 arranged horizontally 70 one upon the other edgewise. Two sets of the boards 4 at the opposite sides of the center occupy converging planes and at the point of intersection of said planes is a post 5 provided with grooves 6 receiving the 75 adjacent ends of the adjacent sets of boards 4, the said grooves being preferably formed by securing rigidly to the posts 5 in any suitable manner the strips 7, 8 and 9 which extend preferably for the full length of the 80 post. The posts 5 in conjunction with the strips 9 form grooves 10 for the reception of the opposite ends of a set of boards 11 which constitute a partition between the front chamber 13 and the rear chamber 14, 85 the intermediate or side chambers 15 being accessible from the front chamber by the removal of partition boards between said chambers.

When the partition is erected it is apparent that it braces itself from every direction and consequently is not endangered should only a single chamber be filled with grain or the like.

When the partition is being erected, temporary braces, not shown, will be employed to hold the posts 5 in an upright position at the desired points, said braces being unnecessary after sufficient number of the boards 4 have been positioned to reliably 100 hold the posts 5 in an upright position. Because of this the temporary partitions are not shown.

In transferring grain from chamber 14 to chamber 13, it will be necessary to slide the 105 uppermost boards 11 upwardly out of the grooves 10 as the quantity of grain in chamber 14 diminishes and when access to the contents of either of the chambers 15 is desired, the same method is followed with respect to the front set of boards 4 of said 110 chambers or either of them.

If desired certain of the boards 11 or 4 at a suitable height may be provided with port holes or chutes, not shown as they are in common use in the exterior walls of bins of 5 this character and therefore need not be illustrated.

If the owner desires to provide chambers of different capacity he can do so by setting the posts 5 at the desired points within the 10 bin and the desired distances apart and then use boards 4 and 11 of proper length to extend between said posts and the retaining strips 2 and if necessary the strips 2 can be set at different points within the bin as will 15 be readily understood. In all cases, however, the boards connected with each of the posts 5 should extend convergingly toward said post from planes forward and rearward of the same so that in conjunction with 20 boards 11, the partition shall brace itself from pressure imposed in any direction. It is desirable to have the chamber 13 always of sufficient capacity or size to provide room enough for one to stand within the same and 25 remove or replace any of the boards 4 and 11 and where the bin is of considerable height as is usually the case, to keep a ladder of some sort within chamber 13 to give access to the bin when filled to the height of 30 five feet or more.

From the above description it will be apparent that I have produced a storage bin for grain or the like, possessing the features of advantage enumerated as desirable, and 35 I wish it to be understood that while I have illustrated and described the preferred embodiment of the invention, I reserve the right to make all changes falling within the spirit and scope of the appended claims.

40 I claim:—

1. A bin provided with a partition comprising a pair of upright posts within the

bin, boards extending from one of said posts to the other and held in place by and bracing said posts and sets of boards diverging 45 laterally and extending forwardly and rearwardly from said posts and secured in fixed relation to the wall of the bin.

2. A bin provided with a partition dividing it into four chambers and consisting of a pair of posts arranged upright within the bin and provided with opposite vertical grooves, boards arranged edgewise one upon the other and fitting at their opposite ends in said grooves, four pairs of strips secured within and to the wall of the bin in planes outward, forward and rearward of the planes of said posts and four sets of boards arranged edgewise one upon the other, each set fitting at their outer ends between a pair 60 of said strips and at their inner ends engaging said posts for slidable movement upward or downward.

3. A bin provided with a partition dividing it into a front chamber, a rear chamber and two side chambers, and comprising a pair of upright posts spaced apart and provided with opposite vertical grooves, with rearwardly and outwardly facing vertical grooves and with forwardly and outwardly facing vertical grooves, sets of strips within the bin and spaced apart to provide grooves opposite the forwardly and outwardly facing grooves of said posts, and boards arranged edgewise one upon the other and fitting at their outer ends in the grooves formed by said strips and at their inner ends in the opposing grooves of said posts.

In testimony whereof, I affix my signature, in the presence of two witnesses.

EMANUEL E. NORQUIST.
